[57] CLAIM

The ornamental design for the container for baked food products, as shown and described.

DESCRIPTION

FIG. 1 is a perspective view of a container for baked food products showing my new design;
FIG. 2 is a side elevational view thereof;
FIG. 3 is a side elevational view thereof; rotated 90 degrees in either direction from the position shown in FIG. 2;
FIG. 4 is a top plan view thereof; and,
FIG. 5 is a bottom plan view thereof.
